UNITED STATES PATENT OFFICE

132,635

DESIGN FOR A HAT

Vera Kelsey, New York, N. Y.

Application April 20, 1942, Serial No. 106,625

Term of patent 3½ years

To all whom it may concern:

Be it known that I, Vera Kelsey, a citizen of the United States, residing in New York city, in the county of New York and State of New York, have invented a new, original, and ornamental Design for a Hat, of which the following is a specification, reference being had to the accompanying drawing, forming part thereof.

Fig. 1 is a front view of a hat showing my new design, and

Fig. 2 is a view of the hat shown in Fig. 1 turned inside out in carrying position.

I claim:

The ornamental design for a hat, substantially as shown.

VERA KELSEY.
